ATTORNEY.

UNITED STATES PATENT OFFICE

CHARLES WEICHOLD, OF CINCINNATI, OHIO

CONCRETE REINFORCEMENT

Application filed April 4, 1927. Serial No. 180,753.

The object of my invention is to produce a reinforcement strip or bar, made of metal, which is to be imbedded in the concrete for strengthening and reenforcing the concrete, 5 in order to keep the concrete in a fixed and normal position, prevent disintegration, and cracking and to prevent undue undulation of the surface of the concrete, thus retaining same in a desired condition.

10 My new reenforcing bar can be used in many ways and varying positions, according to the concrete job worked upon.

It is very simple in construction and highly efficient in use, and is formed in such a manner that no sharp or rough edges or points are present in its outlines and all parts are rounded or curved in contour, to prevent cracking of the concrete.

It is especially adaptable for use in floors, 20 walls, drive ways, walks, steps and kindred concrete constructions.

In the accompanying drawing forming part of this specification:

Fig. 1, is a plan view of one form of my re- 25 enforcing bars,

Fig. 2, is a side view thereof, the dotted lines in said Figs. 1 and 2 represent the bar being straight, if it is desired to use such form,

30 Fig. 3, is a detail plan view showing two bars joined, to form a continuous length, the bars broken off at their ends,

Fig. 4, is a side view of parts shown in Fig. 3,

35 Fig. 5, is a section taken on line 5—5 of Fig. 2,

Fig. 6, is a section taken on line 6—6 of Fig. 4,

40 Fig. 7, is a plan view of a drive way section, with the ends broken away showing one form of using my reenforcing bars in such a concrete construction, and

Fig. 8, is an enlarged section, taken on line 45 8—8 of Fig. 7.

The bar is usually formed of one metal piece, having a body and a base with flanges 1, 1, connected by a raised U section 2, with the flanges 1, 1, extending beyond the raised portion at each end forming extensions as 3,

flat in some instances, and bent downwardly to form legs 4, 4, in other instances.

It will be noted that the flanges 1, 1, and the U part 2 are formed of a curvilinear design to avoid any sharp edges or corners. 55

In order to form continuous bars I provide side extending ears, 5, 5, which overlap flanges 1, 1, when bent upwardly, after two sections of bars 6 and 7 have been pressed together as shown in Fig. 6, these ears 5, 5, prevent any lateral play, and the meeting ends are held together by nails 8, 8, passing through holes 9, 9, in the bars 6 and 7. These nails hold the bars securely together and form a cheap and simple uniting means. 60

In Figs. 7 and 8 the concrete part of a drive way is marked 10 and the cinders 12 and the space below the bars being filled with concrete and above the bars shown at 13, the concrete extends several inches above the uppermost parts of the bars. 65

In Figs. 7 and 8 I show one detailed method for using my new reenforcing bars; in Fig. 7, I show how they can be crossed, one above the other like an X and others placed on each side 75 thereof and some in between the rows of the X's and in Fig. 8, it is shown how said bars are crossed; in Fig. 7, it will be seen that the bars are placed and distributed in a road way so that the wheels of a vehicle will not in any manner be unsupported across the entire area of the said road, and in such construction the concrete will not crack and its surface will be supported in a uniform manner, and strengthened in every part thereof. 80

It is shown in Figs. 2 and 3 how reenforcing bars may be lengthened by joining them together; in this way any length may be used. 85

While I have shown the bars used in connection with flat work they may also be used in connection with upright walls and in such constructions these joined strips may be used to advantage, altho the single bars may also be used, and for strength and support some of the strips may extend in a horizontal direction to join the vertical or upright strips and distributed in a manner to support the wall in all sections or parts thereof. 90

The reenforcing strip or bar may be used as shown in Figs. 5 and 6, or the same may be inverted, which ever way of use, is found most practical by the particular job of concrete work.

5 It will be noted that the ends 15 of the part 2 are rounded and gradually tapered to a point and are thus shaped to prevent sharp corners.

10 While my reenforcing bar may be made of any kind of material I prefer to stamp the same out of sheet metal of varying thicknesses, as required.

15 It will be noted that the edge 20, where the feet 4 are turned downwardly is also rounded, to further prevent cracking of the concrete, the same as all the other rounded parts of the bar, and if desired the feet 4 may be turned upwardly in an opposite direction from that shown in Figs. 1 and 2.

20 It will readily be observed that changes and modifications may be made, without departing from the spirit of the invention, and I claim all such changes and modifications 25 which may fall within the scope of this specification and the appended claims.

What I claim as new and my invention and desire to secure by Letters Patent is:

30 1. In concrete construction, reenforcing bars, said bars having an elongated U shaped rib with lateral flanges at the base thereof, one bar provided with a head having ears at its edges, the end of one of said reenforcing bars lying within said head and ears and means 35 for holding them together to form an elongated reenforcing bar.

40 2. In a roadway or the like, a layer of concrete, spaced lines of metal reenforcing bars embedded in the concrete, the bars of each line being in overlapping relation with one end of each bar arranged alongside of the adjacent end of the next bar, and crossed bars embedded in the concrete between said lines of bars.

45 3. In concrete construction, bars imbedded in the concrete, each of said bars having an elongated U-shaped rib with lateral flanges at the base thereof, said rib being rounded, the ends of the bar having flat pliant extensions which may be readily bent downwardly 50 to form legs of varying lengths for supporting the bar in proper position while it is being imbedded in the concrete.

55 4. In concrete construction, a foundation, metal bars having pliant legs resting on the foundation and supporting the main portions of the bars above the foundation, each bar having an elongated U-shaped rib with lateral flanges at the base thereof, and a layer 60 of concrete arranged on the foundation, said bars being imbedded in the layer of concrete.

65 5. A reenforcing element for flat concrete layers which are subjected to moving loads, comprising a metal bar having an elongated U-shaped rib with lateral flanges at the base

thereof, the end portions of the bar being wider than the main portion thereof, and being pliant to permit the same to be readily bent downwardly to form legs adapted to rest on a foundation of a concrete layer in which 70 the bar is to be imbedded.

In testimony whereof, I affix my signature at the city of Cincinnati, county of Hamilton and State of Ohio, this 24th day of March, 1927.

CHARLES WEICHOLD.
